HOUSING FOR AN ACTUATOR OR THE LIKE FOR HYDRAULIC SYSTEMS

John Rollitt, Copmanthorpe, York, England, assignor to
Armstrong Patents Co. Limited, Yorkshire, England,
a company of Great Britain

Filed Aug. 18, 1959, Ser. No. 57,209

Claims priority, application Great Britain Feb. 28, 1959

Term of patent 14 years

(Cl. D65—1)

Fig. 1.

Fig. 2.

FIG 3.

FIG 4.

FIG. 1 is a perspective view of a housing for an actuator or the like for hydraulic systems;

FIG. 2 is an elevational view of the side of the housing opposite that shown in FIG. 1;

FIG. 3 is a top plan view thereof; and

FIG. 4 is an end elevational taken from the left of FIG. 2.

I claim:

The ornamental design for a housing for an actuator or the like for hydraulic systems, substantially as shown.
